UNITED STATES PATENT OFFICE.

OSCAR E. W. BRUNK, OF ST. LOUIS, MISSOURI, ASSIGNOR TO JOSEPH J. MARX, OF ST. LOUIS, MISSOURI.

PAD-SUPPORT FOR PRESSING-MACHINES.

1,276,717.

Specification of Letters Patent. Patented Aug. 27, 1918.

Application filed October 15, 1917. Serial No. 196,577.

To all whom it may concern:

Be it known that I, OSCAR E. W. BRUNK, a citizen of the United States, residing at the city of St. Louis and State of Missouri, have invented a new and useful Pad-Support for Pressing-Machines, of which the following is a specification.

This invention relates to machines for pressing garments and other kinds of fabric, and has special reference to the device for supporting the garments or fabrics upon the buck of the machine.

An object of the invention is to provide a frame adapted to be placed upon the heated buck of the pressing machine to support the pad upon which the garment or fabric is placed so that the pad will not be burned or scorched, and as a result thereof become broken or disintegrated and drawn through the foraminous top plate of the buck of the machine.

Another object is to provide a removable device of the character mentioned comprising spaced upper and lower walls composed of woven wire through the spaces of which the steam may freely pass during the operation of the pressing machine, but which will support the pad so that it will not be burned or scorched and as a result thereof be drawn through the head of the buck.

In the accompanying drawings, in which I have illustrated the invention,

Figure 1 is a front elevation, partly in section, of a pressing machine having the present invention in connection therewith.

Fig. 2 is a plan view with a part of the pad removed to illustrate the construction of the frame.

Fig. 3 is a cross sectional view on the line 3—3 of Fig. 2.

The pressing machine with which I have illustrated my present invention is similar to that disclosed in the patent to Benjamin Weinberger, No. 1,193,093, dated August 1, 1916. The moistening, heating and pressing mechanism will be generally described in order that the present invention may be fully understood, not only as to its construction and arrangement, but also as to its co-operation with a pressing machine. The machine of that patent includes a press head 1 which is movable toward and away from the buck or support by which the garment or fabric to be pressed is supported. The

buck is in the form of a frame and comprises a foraminous top plate 2 secured to a frame so as to form therewith a chamber 3 which is closed from communication with another chamber 4 in the frame.

Steam from any available source of supply may be admitted to the interior of the press head through a supply pipe 5 having a normally closed valve 6 arranged to be opened at will of the operator by manipulation of a handle 7.

As illustrated the foraminous top plate 2 forms the upper wall of the chamber 3. Heretofore machines of this type have been equipped with pads secured directly to the top plate of the buck for receiving and supporting the garment or cloth to be pressed by pressure of the head 1. In the machine shown, the buck may be heated by steam admitted to the chamber 4 through a pipe 8, though the buck may be otherwise heated, if desired. The garment or cloth is moistened by steam forced from the head 1 through the garment and the openings through the top plate 2 into the chamber 3 from which the steam is withdrawn and discharged through a pipe 9 controlled by the manipulative valve 10 and connections therefrom. A machine in which the pad is secured directly to the top plate 2 of the heated buck burns and scorches the pad, so that it breaks and parts thereof are drawn into the chamber 3 and thence into the discharge pipe. It is with machines of this class, irrespective of the particular arrangement thereof, that my present invention is arranged to co-operate.

My present invention consists of a device in the form of a hollow foraminous frame adapted to be placed upon the supporting frame or buck and to support the pad out of contact with the top plate of the buck so that the pad will not be subjected to the destructive action of the heat as formerly.

As illustrated the device is in the form of a frame the contour of the side edges of which conform generally to the edges of the upper wall of the buck. The frame comprising an upper wall 11 and a similar lower wall 12, both formed of woven wire, as shown, and retained in spaced relation by an interposed spacing strip 13 placed between and secured to the upper and lower walls adjacent to their edges. In addition there are several other spacing strips 14 arranged

and secured in proper relation and position between the upper and lower walls, so that said walls will not be bent when the garment or fabric is pressed thereon. It is preferable, though not essential, that the spacing strips 13 and 14 be of some fabricated material, such as packing.

To this frame the pad 15, composed of fabric or other appropriate material, is secured for receiving and supporting the garment or fabric to be pressed. The pad may be secured to the frame by any desired fastening connections, such, for instance, as the bands 16 in connection with the pad and passing around or otherwise engaging the frame.

The frame thus constructed is intended to be placed upon the top plate 2 of the buck so as to support the pad 15 out of contact with the heated parts of the pressing machine. In operation the device is applied as illustrated in Fig. 1 in which the garment or fabric may be placed upon the pad, and then subjected to pressure by operation of the head 1 in the usual manner. During this operation steam is introduced through the head and upon and into the garment by opening the valve 6 by means of the handle 7, thereby moistening the garment simultaneously with the application of the mechanical pressure. As usual, the steam for moistening the garment is admitted only for an instant, while the garment is under pressure, whereupon the head is elevated in the usual manner and the valve 10 is opened to allow any steam or moisture of condensation

which may be retained in the garment or in the frame supporting the same to be withdrawn. In this manner the garment is quickly dried.

The frame thus constructed is readily interchangeable from one machine to another and requires no binding connections to retain it in place. It is apparent that the specific construction and arrangement of the frame may be varied without in the least departing from the invention. I do not restrict myself to any specific features other than as set forth in the appended claims.

What I claim and desire to secure by Letters Patent, is:

1. A device of the character described, comprising an upper frame composed of woven wire, a lower frame also composed of woven wire, and a series of spacing elements interposed between and contacting with both of said frames and maintaining said frames in their spaced relation.

2. A device of the character described, comprising a lower frame composed of woven wire, an upper frame also composed of woven wire, a fabricated spacing strip interposed between the edge portions of the upper and lower frames and maintaining the edge portions of said frames in spaced relation and preventing the passage of steam laterally from between said frames, and a series of additional spacing strips also interposed between said frames and supporting them in spaced relation.

OSCAR E. W. BRUNK.
